ATTORNEYS.

UNITED STATES PATENT OFFICE.

SPENCER K. BROWN, OF SYRACUSE, NEW YORK.

SOCKET WRENCH HEAD.

Original application filed March 3, 1921, Serial No. 449,305. Divided and this application filed October 14, 1921. Serial No. 507,645.

To all whom it may concern:

Be it known that I, SPENCER K. BROWN, a citizen of the United States, and a resident of Syracuse, in the county of Onondaga and State of New York, have invented a certain new and useful Socket Wrench Head, of which the following is a specification.

This invention has for its object a wrench head having particularly simple and efficient means for guiding the nut or angular head of a bolt or screw into the angular socket of the wrench head especially when the wrench head is power driven.

15 The invention consists in the novel features and in the combinations and constructions hereinafter set forth and claimed.

In describing this invention, reference is had to the accompanying drawings in which 20 like characters designate corresponding parts in all the views.

Figure 1 is an elevation, partly in section, of a wrench head embodying my invention.

25 Figure 2 is a face view of parts seen in Fig. 1.

Figure 3 is a detail view of the contiguous part of a machine for which my wrench head is particularly adapted.

30 The construction of the machine forms no part of this invention, but forms the subject matter of my pending application, Sr. No. 449,305, filed March 3, 1921, of which application this is a division.

35 1 designates the wrench head which has a polygonal socket 2 for receiving the nut or the angular head of a bolt or screw.

The means for guiding the bolt head or nut into the polygonal socket as here shown 40 comprises a circular recess at the entrance of the polygonal socket, the recess being of as great diameter as the diagonal of the socket and as here shown, the recess is a substantially cylindrical countersunk recess 45 3 at the entrance end of the socket, the socket opening through the bottom of the recess and the corners 4 of the socket being substantially coincident or flush with the wall of the recess as seen in Fig. 2. The wrench 50 head is designed particularly to be used in connection with a rotating and axially movable driving member as a spindle, which rotates rapidly and during the rapid rotation of the wrench head when brought down 55 on the nut or the head of a bolt, the recess

3 initially receives the bolt head or nut and rotates thereon until during the axial feeding movement of the spindle, the bolt head or nut coincides with the socket 2 and slips thereto.

60 6 designates the spindle which is suitably supported by a frame 7 and which is rotated by any suitable means as a rotating driver 8 having a gear 9 thereon which meshes with the driving gear, not shown, the driver 8 65 being connected to the spindle through a friction clutch 10. The spindle 6 is fed axially usually by hand.

The spindle as here shown has a head 12 at its lower end which is keyed thereto at 70 13 and which is held from displacement by a screw 14.

75 This head 12 rotatably fits in a tool holder 15 suitably journaled in the frame 7 and in which is also supported a wrench head 1, the wrench head being shown as rotatably mounted in a neck 16 at the lower end of the tool holder and having an enlargement or collar 17 which rotatably fits within the tool holder and also shoulders against the 80 bottom wall of the tool holder at 15.

The head 12 and the inner end of the wrench head are provided with means arranged to interlock during downward movement of the spindle whereby the wrench 85 head rotates with the spindle, this means being here shown as interlocking teeth 19 and 20 on the head 12 and the wrench head 1 respectively.

These teeth and the coaction of the spindle with the wrench head form no part of 90 this invention, but constitute the subject matter of my pending application above referred to, and the construction and operation of the spindle are pertinent to the 95 present invention only in so far as the operation of the recess 3 at the entrance of the hexagonal socket of the wrench is concerned when such recess is guiding the nut or bolt head into the socket during rapid rotation 100 of the wrench head by the spindle 6.

What I claim is:

1. A wrench head having a polygonal socket, and a circular recess at the mouth of the socket concentric with the axis of the 105 socket for guiding the nut or screw head into the socket, such recess being of as great diameter as a diagonal of the socket, substantially as and for the purpose described.

2. A wrench head having a polygonal 110

socket, and an annular countersunk recess at the entrance of the socket, the socket opening through the bottom of the recess, substantially as and for the purpose specified.

3. A wrench head having a polygonal socket, and an annular countersunk recess at the entrance of the socket, the socket opening through the bottom of the recess, the 10 corners of the polygonal socket being substantially flush with the inner annular wall of the recess, substantially as and for the purpose set forth.
4. In a machine of the class described,

the combination of a rotatable and axially movable driving member and means for actuating said member, of a wrench head movable with said member, the wrench head having a polygonal socket, and an annular countersunk recess at the entrance of the 15 socket, the socket opening through the bottom of the recess, substantially as and for the purpose described.

In testimony whereof, I have hereunto signed my name, at Syracuse, in the county 20 of Onondaga, and State of New York, this 13th day of October, 1921.

SPENCER K. BROWN.
